Mounting Having a Large Central Gem Overlying Adjacent Small Gems

Henry Peterson, New York, N. Y.

Application December 28, 1953, Serial No. 400,714

6 Claims. (Cl. 63—28)

The present invention relates to mountings for jewels or precious stones, and especially to mountings for solitaire brilliants, such as diamonds or the like, of the type associated with finger rings and similar articles of jewelry.

The present invention is particularly directed to Tiffany style mountings for solitaires, especially of the type formed with highly polished, light reflecting surface areas surrounding the setting for the brilliant, intended to create or provide an illusion enhancing the appearance of the brilliant.

Such mountings of the general type described above, to which the present invention relates, as heretofore made, are formed with a top platform or table that is larger than and provides marginal portions surrounding the cavity or aperture into which the brilliant is set, which marginal surface portion is subdivided into concave or otherwise faceted, highly polished, light reflecting surface areas, whose reflected light provided the diffused or scattered brilliance which enhanced the appearance of the solitaire.

However, the effect or illusion created by the light reflecting surface areas surrounding the center brilliant in the mountings of the prior art, though enhancing the appearance of the mounting top or table by increasing the amount of light scintillated and reflected from it, did not actually create an impression of enlargement or enhancement of the size of the brilliant set thereto, and did not make such brilliant appear larger than it actually was.

It is an object of the present invention to provide a mounting or mounting top for the setting of a solitaire brilliant or the like, of the character described, such as is used in connection with rings or other, similar articles of jewelry, such as earrings, or the like, which will create the illusion of magnifying the brilliant or like and make it appear larger than its actual size.

It is another object of the present invention to provide brilliant mountings of the character described which are highly effective for their purpose and which may be simply, easily and readily formed and as simply and easily used, at relatively little increase in cost over the conventional mountings of the same type as heretofore used.

It is a further object of the present invention to provide brilliant mountings of the character described which are attractive in appearance in respects other than and additional to their brilliant magnifying effects.

The foregoing and other advantages and superiorities of the brilliant mountings of the present invention will become more readily apparent to those skilled in the art from the several embodiments thereof shown in the accompanying drawing and from the description following. It is to be understood, however, that such embodiments are shown by way of illustration only, to make the principles and practice of the invention more readily comprehensible and without any intent of limiting the invention to the specific details therein shown.

In the drawings:

2

Fig. 1 is an enlarged, top plan view of one embodiment of a mounting for a brilliant contemplated by the present invention;

Fig. 2 is an enlarged vertical sectional view of such setting, taken on line 2—2 of Fig. 1;

Fig. 3 is an enlarged top plan view of the mounting of Fig. 1, shown with a brilliant and auxiliary or satellite brilliants set into place;

Fig. 4 is an enlarged plan view of another embodiment of a setting of the present invention, formed with differently shaped and arranged slight reflecting areas;

Fig. 5 is a similar top plan view of still another embodiment of a mounting of the present invention, formed with still differently shaped and arranged light reflecting surfaces.

Referring now more specifically to the accompanying drawing, and with special reference to the embodiment of the invention illustrated in Figs. 1—3, thereof, of mounting, generally designated as 10, which may most effectively be formed of a white metal, such as white gold, may but need not necessarily be of the Tiffany or box type, that may, if desired, be cast or formed integrally with the shank of a finger ring or with any other suitable article of jewelry (not shown), or may be suitably secured thereto. Such mounting 10 is shown as comprising a platform or table, 11, from which depend, preferably integrally and preferably slightly convergently, the side walls, 12, in which are formed or cut out the light admitting openings 13 and 14.

The table 11, or similar mounting surface, may preferably be of roughly or approximately rectangular shape or outline, and is provided at its center, at a point removed from its edges or its boundaries, with a central opening or cavity, 16, adapted to serve as a seat or setting for a brilliant, such as a diamond, 18. The marginal portions of the table 12, surrounding the opening 16, are divided into a plurality of concave areas, 17, extending outwardly from the opening 16, preferably in opposed directions, each to one edge of the table. The areas 17 may be smooth surfaced or may be faceted, as desired, and may preferably be formed to abut or intersect with one another, as at 19.

Each of the concave areas 17 is formed with a highly polished or shiny light reflecting surface and, because of its concave shape, reflects light in a diffused or scattered manner, in all directions.

Rising from the table 11, around the opening 16, are a plurality of posts, 20, which are preferably four in number and are arranged in a rectangle, one each at the intersection between areas 17, which posts are arranged and formed to be worked and bent by the jewel setter to serve as prongs for retaining the brilliant 18 within the opening 16. Such diamond or brilliant 18 is the principal ornament of the mounting and is of substantial size and, together with the surrounding light reflecting areas 17, provide the mounting with an enhanced brilliant effect.

However, as heretofore explained, such enhancement effect of light reflection or brilliance falls short of being an effect of magnifying the appearance of the diamond or brilliant to make it look larger than its actual size. To obtain the latter effect, I have invented improvements consisting of additional apertures, 21, of considerably lesser size than the aperture 16 and surrounding the same, to serve as settings for relatively small sized brilliants, 22. Preferably, one aperture 21 is provided in each of the areas 17, preferably at the lowermost point of its concavity.

The setting openings 21 are preferably so arranged relative the opening 16 that the satellite brilliants or diamonds, 22, abut against and may even underlie, part-

ly, the central brilliant, 18, which generally sits higher in its opening 16, so that the latter may serve as part of the means for retaining the brilliants 22 in place, as illustrated. Additional means for retaining the smaller brilliants 22 in place may be provided in the form of the relatively smaller pins or posts, 23, which rise from each of the areas 17, in proximity to the apertures 21, which may be worked and bent by the setter to serve as retaining prongs. Such posts 23 may be two in number and may be arranged along a diameter of the opening 21, or nearer toward the edge of the table 11.

I have found that by this arrangement of setting openings 21 for relatively small and relatively low cost satellite brilliants in each of the concave reflecting areas 17, in close proximity to the main, larger, central brilliant setting 16, an effect is obtained, when the several brilliants are set in place, of a magnified central brilliant 18, of a size that would cost far more than the combined cost of the actual central brilliant 18 and the satellite brilliants 22.

In the embodiments of Figs. 4 and 5, the principle of the invention is carried out with tables 12 having different forms and different arrangements of reflecting concave areas 17. Thus, in Fig. 4, the areas 17, are of triangular formation, centering on the center of the opening 16, and cover the entire table except for the marginal beads, 25. This distinguishes from the table 12 of Fig. 1, wherein the corners of the table are provided with floral relief ornamentation, 26. In the embodiment of Fig. 5, the reflecting areas 17 are shell shaped, to provide arcuate side edges, 27, for the table 12, which is additionally provided with corner knobs, 28.

This completes the description of the brilliant mountings of the present invention and of the articles of jewelry that may be formed with them. It will be readily apparent that they are highly effective for the purpose of magnifying, at relatively little cost, the appearance of the solitaire brilliant generally used with mountings of the same type. It will also be apparent that the mountings themselves may be formed and provided at none or relatively little increase in cost over the similar mountings heretofore used and that they may be set with brilliants with relative ease and economy.

It will be further apparent that numerous variations and modifications in the mountings of the present invention may be made by anyone skilled in the art, in accordance with the principles of the invention hereinabove set forth and without the use of any inventive ingenuity. I desire, therefore, to be protected for any and all such variations and modifications that may be made within the spirit of the present invention and the scope of the claims hereto appended.

What I claim is:

1. A mounting for a diamond or the like, comprising a top plate having a relatively large opening formed therethrough at approximately its center and adapted to seat a relatively large diamond and means on the surface of said top plate for holding said diamond in place, said top plate having a plurality of relatively smaller openings formed therethrough, evenly, sparsely and circumferentially disposed around said larger central opening, each adapted to seat a diamond of relatively smaller size having a central flat top section, in position to have said smaller diamond underlie and abut the underside of said larger diamond, with said larger diamond overlying a part of said flat top section of each of said

smaller diamonds, and means adjacent to each of said smaller openings for holding a smaller diamond in place therein, said top plate having a smooth, concaved, light reflecting surface extending radially inwardly toward said larger central opening and curving upwardly away from and surrounding and extending beyond each of said smaller openings and the smaller diamond set thereinto.

2. The mounting of claim 1, wherein side wall portions depend from the edges of said top plate, said side wall portions having light admitting openings formed therethrough.

3. The mounting of claim 1, wherein said top plate is of approximately rectangular shape and wherein each of said smaller openings is formed along one of the shortest radii from said center opening to the edges of said top plate.

4. The mounting of claim 1, wherein said top plate is of approximately rectangular shape and has a side wall depending from each edge thereof, each of said side walls having a light admitting opening formed therethrough, and wherein each of said smaller openings is formed along one of the shortest radii from said central opening to an edge of said top plate.

5. An article of jewelry, including a mounting comprising a top plate having a relatively large opening formed in the center thereof, a relatively large diamond set in said central opening, means on the outer surface of said top plate holding said diamond in place, said top plate having a plurality of relatively smaller openings formed therethrough, evenly, sparsely and circumferentially disposed around said central opening and in close proximity thereto, each of said smaller openings having a relatively smaller diamond set thereinto in position having a portion thereof underlie and abut the bottom of said larger diamond with said larger diamond overlying a portion of the flat top section of each of said smaller diamonds, and means adjacent to each of said smaller openings holding said smaller diamonds in place therein, said top plate having a smooth, concaved, light reflecting surface extending radially inwardly toward said larger central opening and curving upwardly away from and surrounding and extending beyond each of said smaller openings and the smaller diamond set thereinto.

6. The article of jewelry of claim 5, wherein said top plate is of polygonal shape and has side wall portions depending from the edges thereof, each of said side wall portions having a light admitting opening formed therethrough, and wherein each of said smaller openings is formed along one of the shortest radii from said central opening to an edge of said top plate.
